UNITED STATES PATENT OFFICE.

SAMUEL T. COFFING, OF ATTICA, INDIANA.

RUST PREVENTING AND REMOVING COMPOSITION.

SPECIFICATION forming part of Letters Patent No. 719,190, dated January 27, 1903.

Application filed September 16, 1902. Serial No. 123,637. (No specimens.)

To all whom it may concern:

Be it known that I, SAMUEL T. COFFING, a citizen of the United States, residing at Attica, county of Fountain, and State of Indiana, have invented certain new and useful Improvements in Rust Preventing and Removing Compositions, of which the following is a specification.

My invention relates to greases and heavy oils; and the object thereof is to prevent and remove rust and to brighten the tool or piece of metal on which it has been applied. It is especially adapted for use on saws of all descriptions.

My composition consists of the following ingredients, combined in the proportions stated, viz: beeswax, one part; beef - tallow, two parts; sperm-oil, one and one-half parts, and pulverized pumice-stone one-half part.

In compounding the above ingredients the beeswax, beef-tallow, and sperm-oil are first put in a pot over a moderately-hot fire and boiled, stirring continually until all are thoroughly incorporated. It is then removed from the fire, and while cooling the pumice-stone is fed to the mixture slowly, stirring all the while, until the pumice-stone is thoroughly mixed with the greases. It may now be put up in small boxes for retail or in large tins for wholesale purposes.

My composition may be applied with the fingers, with a brush, or with a cloth and rubbed until the pumice-stone and grease have removed the rust. It may also be applied to tools and other metal articles and left thereon, so as to prevent rust.

By using the above compound on saws and other tools they are lubricated and kept from rusting at all times and under all atmospheric conditions.

Having thus described my invention, what I claim as new, and desire to secure by Letters Patent, is—

1. The herein-described composition of matter, consisting of beeswax, beef-tallow, sperm-oil and pulverized pumice-stone, substantially as described.

2. The herein-described composition of matter for polishing and removing rust on metal, consisting of one part beeswax, two parts beef-tallow, one and one-half parts sperm-oil, and one-half part pulverized pumice-stone, substantially as described.

In testimony whereof I hereunto affix my signature in presence of two witnesses.

SAMUEL T. COFFING.

Witnesses:

JOE B. HATTON,
I. E. SCHOONOUR.
